UNITED STATES PATENT OFFICE

2,573,556

MOBILE VACUUM STRIPPER FOR CARDING MACHINES

Mitchell S. Fain, Cheshire, Conn.

Application May 20, 1948, Serial No. 28,146

1 Claim. (Cl. 183—67)

1

This invention relates to improvements in card stripping apparatus and relates more particularly to a novel, self-contained, mobile unit for removing matted and waste fibres, dirt, grease and other foreign matter from card clothing.

Periodically it is necessary to remove this accumulated waste material from carding cylinders of all types working on woolens, worsteds, felts, cottons, synthetic fibres, asbestos and mixtures of these materials in original or reworked forms. Card stripping by vacuum means has proven far more satisfactory than the older practice of removing the material by hand. It causes far less injury to the card clothing and it performs the operation much more quickly, thus resulting in shorter periods of shutdown of the carding machine. It is also a far cleaner operation and avoids the dispersion of fine, dust-like particles over the entire surface of the plant and fixtures.

Vacuum card strippers have in the past been invariably of one type, namely a fixed, permanent installation of apparatus including a central collecting unit which provides the necessary vacuum and a receiving tank or other means for effecting a separation of the solid particles from the fluid stream. Such an apparatus also includes a system of ducts leading to all of the machines in the card room. The apparatus requires heavy installation foundations and it operates at relatively less efficiency due to the long ducts from the carding machine to the receiver tanks. Also the apparatus requires in the aggregate a very considerable amount of space, is always in the way of the normal carding operation, and is expensive to install and maintain.

An important object of the present invention is to provide an improved mobile unit which is relatively inexpensive to construct, operate and maintain, which requires little space, and which may be moved completely out of the carding area when not in use.

A further object of the invention is to provide a novel card stripper which requires ducts of minimum length, thus reducing losses due to friction. Whereas the apparatus of the present invention is designed primarily as a vacuum stripper for card clothing it nevertheless will have general utility throughout a textile plant, particularly in cleaning operations of all descriptions.

A further object of the invention is the provision of an improved collector tank for vacuum cleaning systems wherein the separation of the solid particles from the air is complete and in-

stantaneous and wherein clogging of the air filters is reduced to a minimum, thus reducing servicing time. The tank of the present invention also eliminates the need for cloth filters which were required in prior equipment.

In the drawings:

Fig. 1 is a side elevation of a vacuum card stripper embodying the present invention, the view also showing a partial side elevation of a conventional card with the stripping nozzle attached thereto.

Fig. 2 is a side elevation of the collector tank.

Fig. 3 is a broken vertical section taken through the upper section of the tank.

Fig. 4 is a broken section taken through the lower section thereof.

Fig. 5 is a broken section taken on line 5—5 of Fig. 2.

The vacuum stripping equipment of the present invention is arranged to be mounted on a mobile unit comprising a base 10 carrying wheels 11 at one end thereof. A draw-bar 12 at the opposite end of the base controls swivel movement of wheels 13 and also enables the unit to be pushed or pulled to its desired location.

A vertical, generally cylindrical collector tank 14 is rigidly mounted at one end of the base and is formed adjacent its upper end with an inlet port comprising a fitting 15 to which is connected a flexible duct 16 which carries a nozzle 17 at its opposite end. This nozzle is shown as being supported by a traverse bar 21 associated with the main cylinder of a carding machine indicated generally by the reference numeral 22. Neither the traverse bar nor the card form any part of the present invention and any type of nozzle may be employed at the outer end of duct 16.

The upper section of tank 14 is further formed with an outlet port comprising a fitting 23 connected with a flexible duct 24. The outer end of the duct is connected by means of a fitting 25 with a relatively powerful vacuum pump 26 also mounted on the base. A flexible coupling 27 connects the pump shaft 31 with shaft 32 of a motor 33 also mounted on the base. Pressure in the tank is indicated by vacuum gauge 34.

Reference is now made to Figs. 3, 4 and 5 which show the details of construction of the collector tank. The solid particles which have been stripped from the card clothing collect at the bottom of the tank and rest upon lower wall 30 and are removed from the tank through access door 35 which is mounted by hinges 36 on a generally rectangular frame 31 at the lower end 55 of the tank. Locking means 40 may be employed

for retaining the door closed in fluid-tight relation with the tank.

The tank is formed with a horizontal partition or wall 41 spaced from upper wall 42, thus dividing the tank into an upper chamber 43 and a lower chamber 44. Fitting 15 leading to duct 16 terminates in an elbow 45 which passes through such partition. A baffle plate 46 of curved or angular contour may be secured on the lower surface of partition 41 between the elbow 43 and the center of the partition for the purpose of deflecting the solid particles downwardly as they enter lower chamber 44.

Fitting 23 connected with duct 24 communicates with upper section 43 of the tank. At its inner end elbow 23 is formed with a flange 50 and a screen 51 is mounted thereon by means of a retaining ring 52 held by screws 53.

A central opening 54 in partition 41 is closed by a foraminous screen 55, preferably made from metallic wire, the screen being secured in place by a retaining ring 56 and bolts 57. For the purpose of examining and replacing screens 51 and 55 the upper wall 42 is provided with an access opening 61 which is closed by a removable closure plate 62.

The elbows, the horizontal partition, the frame supporting the lower access door, etc., are shown as secured in place by means of welding. It will be understood, however, that any other desired construction may be employed.

No particular cooling means for the pump are shown although if desired a fluid cooling medium may be employed.

In use the motor is energised, thus creating a very considerable degree of vacuum within collector tank 14. Any suitable means may be employed for moving nozzle 17 relative to the carding cylinders while the latter are in motion and this causes the accumulated material on the card clothing to be removed in an almost continuous strip. The material enters the lower section 44 of the tank with considerable velocity and the weight of these solids carries them to the bottom of the tank while the air passes upwardly through screen 55 and out of the tank through screen 51.

While one form or embodiment of the invention has been shown and described herein for illustrative purposes, and the construction and arrangement incidental to a specific application thereof have been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles hereof.

What I claim is:

A vertical, generally cylindrical collector tank for a vacuum stripper for carding cylinders, said tank being provided with a horizontal partition adjacent its upper end dividing the tank into upper and lower sections, the tank and the partition having openings therein and a duct passing through such openings and leading downwardly into the lower tank section, the partition having a second opening therein, and a foraminous filter covering such opening, a baffle disposed between said opening and the duct, an outlet duct, the upper section of the tank having an opening for receiving such outlet duct, a foraminous filter covering the inner terminal of such duct, the upper and lower sections of the tank having access openings and removable closures for such openings.
